UNITED STATES PATENT OFFICE

133,176

DESIGN FOR A SHOE SOLE

Jon Gregg, Flemington, N. J.

Application May 28, 1941, Serial No. 101,205

Term of patent 7 years

To all whom it may concern:

Be it known that I, Jon Gregg, a citizen of the United States of America, residing at Flemington, county of Hunterdon, and State of New Jersey, have invented a new, original, and ornamental Design for a Shoe Sole, of which the following is a specification, reference being had to the accompanying drawing, forming a part thereof.

Fig. 1 is a side view of a shoe sole showing my new design.

Fig. 2 is a bottom view thereof.

I claim:

The ornamental design for a shoe sole, as shown.

JON GREGG.
